(57) **CLAIM**

The ornamental design for a torso trainer, as shown and described.

DESCRIPTION

FIG. 1 is a perspective view of a torso trainer showing our new design.

FIG. 2 is a front view of the torso trainer.

FIG. 3 is a rear view of the torso trainer.

FIG. 4 is a left-side view of the torso trainer.

FIG. 5 is a right-side view of the torso trainer.

FIG. 6 is a top view of the torso trainer; and,

FIG. 7 is a bottom view of the torso trainer.

The broken lines in the drawings are for the purposes of illustrating portions of the torso trainer, which form no part of the claimed design.
